UNITED STATES PATENT OFFICE.

HUBERT TOWNSEND FOOTE, OF NEW ROCHELLE, NEW YORK.

SURGICAL APPLIANCE.

No. 807,160.

Specification of Letters Patent.

Patented Dec. 12, 1905.

Application filed October 27, 1904. Serial No. 230,238.

To all whom it may concern:

Be it known that I, HUBERT TOWNSEND FOOTE, a citizen of the United States, and a resident of New Rochelle, in the county of 5 Westchester and State of New York, have invented a new and Improved Surgical Appliance, of which the following is a full, clear, and exact description.

This invention relates to surgery; and its 10 object is to provide a new and improved device for preventing nocturnal emissions of the male human being, the device being simple and durable in construction, designed for convenient attachment to and removal from the 15 penis, and arranged to prevent pressure on the dorsal veins of the penis or on the sensitive urethra, and allowing the wearer to urinate while the device is in position.

The invention consists of novel features and 20 parts and combinations of the same, as will be more fully described hereinafter and then pointed out in the claims.

A practical embodiment of the invention is represented in the accompanying drawings, 25 forming a part of this specification, in which similar characters of reference indicate corresponding parts in all the views.

Figure 1 is a face view of the improvement in an open position. Fig. 2 is a like view of 30 the same in a closed position. Fig. 3 is a sectional plan view of the same on the line 3 3 of Fig. 2. Fig. 4 is a plan view of the same; and Fig. 5 is a side elevation of one of the members, part being in section.

35 The ring A of the device consists of two members or parts A' and A², hinged together at the bottom at A³ and adapted to be closed on top by a spring-band A⁴, secured at one end to the member A' at or near the free end 40 thereof, the said spring-band A⁴ being provided with a row of apertures A⁵, any one of which may be engaged with a pin or stud A⁶, projecting on the outside of the other member A², so that the size of the ring A may be 45 increased or diminished, according to the size of the penis on which the device is to be used. The free end of the member A² is provided with the upturned lugs A⁷, between which passes the spring-band A⁴ to prevent lateral 50 displacement thereof.

To the inside of the members A' A² adjacent to the hinge A³ are secured the lower ends of the spring-arms B B', made segmental and approximately concentric to or parallel with 55 the members A' A². Each spring-arm is preferably made of a piece of thin spring-

steel, cut out to form a plurality of members or prongs, spaced apart, as plainly indicated in Figs. 3 and 5, the free ends of the members being connected with each other by a cross-bar B². On the inside of the members A' A² are secured or formed the pricks or points C C', standing in transverse alinement with the spaces between the parts or members of the spring-arms B B', as plainly indicated in Fig. 3, the outer terminals of the said pricks or points being a distance from the spring-arms B B'. (See Figs. 1 and 2.)

In using the device the wearer disengages the spring-band A⁴ from the stud A⁶ and then swings the members A' A² into an open position, as plainly indicated in Fig. 1, the spring-arms B B' moving with the members A' A² to permit of placing the open device conveniently in position on the penis. The wearer now swings the members A' A² into a closed position, so that the spring-arms B B' snugly fit the sides of the penis, the spring-band A⁴ engaging a corresponding aperture A⁵ with the stud A⁶ to lock the members A' A² of the ring A in a closed position, the entire device being supported by the spring-arms B B' on the penis. Now in case of an erection of the penis during the sleep of the wearer the spring-arms B B' are forced outwardly, and the sides of the swelled penis come in contact with the terminals of the pricks or points, thus causing sufficient irritation for the wearer to wake up and to prevent a nocturnal emission. The wearer on 85 waking up can quickly disengage the spring-arm A⁴ from the stud A⁶ to swing the ring open, and thus disengage the device from the penis.

By the construction shown and described 90 no pressure is exerted by the spring-arms B B' on the urethra or on the veins on the top of the penis, as the urethra extends freely in the space between the attaching ends of the spring-arms B B', and the free ends of the arms B B' do not reach to the top of the penis, and hence cannot press on the veins referred to. By having the members A' A² hinged together and the spring-arms B B' secured to said hinged members the spring-arms constituting the inner ring are adjustable with the outer ring, thereby varying the size of the inner ring and preventing undue pressure or binding on the organ. The spring-arms constructed and arranged as shown and 100 described act as a guard for the points C C', preventing accidental irritation of the wearer.

Having thus described my invention, I claim as new and desire to secure by Letters Patent—

1. The herein-described article of manufacture, comprising a ring made in parts hinged together at one end and adapted to be adjustably connected with each other at the free end, points on the inner face of the ring, and supporting spring-arms attached at one end to the ring parts and movable therewith to vary the size of the opening between the spring-arms.

2. The herein-described article of manufacture, comprising a ring made in parts hinged together at one end, means for adjustably connecting the free ends of the said parts, points on the inside of the ring parts, and yielding spring-arms secured to the ring parts at the inside thereof and divided longitudinally to form spaces therebetween located before the said points, the said spring-arms being movable bodily with said ring parts, for the purpose set forth.

3. The herein-described article of manufacture, comprising a ring made in parts hinged together at one end, one of said parts having a stud means for adjustably connecting the free ends of the said parts, having apertures to receive the stud, points on the inside of the ring parts, and yielding segmental spring-arms secured to the ring parts, at the inside thereof adjacent to the hinged ends of the

ring parts, the said spring-arms extending approximately concentric with the ring parts, and having members spaced apart for their full length for the passage of the said points, 35 the said spring-arms protecting the points and preventing accidental irritation of the wearer, and the arms being adjustable with the said ring parts to vary the size of the opening formed by said arms, the attaching 40 ends of said arms being angular and spaced apart to prevent pressure upon the urethra.

4. The herein-described article of manufacture, comprising a ring made in movably-connected parts, one part having thereon a stud, 45 a spring member permanently joined to one part, and having apertures therein to receive said stud, said ring being provided with points on its inner surface, and yieldable arms supported by the ring parts, at the inner sides 50 thereof, said arms being separated longitudinally by spaces located before said points, and one of the said ring parts having lugs thereon preventing lateral displacement of said spring member.

In testimony whereof I have signed my name to this specification in the presence of two subscribing witnesses.

HUBERT TOWNSEND FOOTE.
